UNITED STATES PATENT OFFICE.

PETER ALBERT HOFFMAN, OF HASTINGS, MINNESOTA.

ENVELOP.

1,125,535.

Specification of Letters Patent.

Patented Jan. 19, 1915.

Application filed April 9, 1914. Serial No. 830,700.

To all whom it may concern:

Be it known that I, PETER A. HOFFMAN, a citizen of the United States, and a resident of Hastings, in the county of Dakota 5 and State of Minnesota, have invented a new and Improved Envelop, of which the following is a full, clear, and exact description.

This invention relates to improvements in 10 envelopes, and has for an object to provide an improved structure which will act properly as a closure or document wrapper while eliminating tapes, rubbers and other similar fastening means.

15 Another object of the invention is to provide an envelop which may be bodily opened and folded whenever desired and secured in a folded position by a suitable clip which does not project beyond the surface of the 20 envelop.

In carrying out the object of the invention a body is provided formed with side and end members adapted to be folded over on the body and secured in a folded position 25 by suitable clips or sliding catches arranged upon one of the side members. These sliding clips or catches are arranged in a fold of one of the side members and formed with a turned-over portion designed 30 to slip over the opposite side member so as to lock the two side members together, and thus hold the envelop against accidental opening. These clips may be formed with one or more raised portions or projections 35 for permitting an easy manipulation of the clips.

In the accompanying drawing—Figure 1 is a perspective view of an embodiment of the invention shown in an open position; 40 Fig. 2 is a perspective view of the structure shown in Fig. 1, but in a closed position; Fig. 3 is a section through Fig. 1 on line 3—3, part of the envelop being shown in its folded position by dotted lines; Fig. 4 is a 45 detailed perspective view of one of the sliding clips.

Referring to the accompanying drawing by numeral 1 indicates a body which acts as the back of the envelop. Extending from 50 the body 1 are side members 2 and 3, and also end members 4 and 5, members 2, 3, 4 and 5 being preferably formed integral with body 1. The end members 4 and 5 are provided with scored or pressed portions 6 and 55 7 which in effect cause a corrugation of the end members, the scored or pressed portions

being arranged adjacent body 1 as clearly shown in Fig. 1. It is not to be understood that the scoring is for the purpose of tearing the end members, but merely for the 60 purpose of allowing the end members to be bent, as shown in Fig. 2, for properly fitting over an inclosure. In making these scored lines or pressed portions the material is merely compressed, and is not removed, 65 whereby the end members retain their original strength but may be easily folded at any desired point for accommodating an inclosure of substantially any thickness. The sides 2 and 3 are also provided with pressed 70 portions 8 and 9 which, however, do not extend to the edges of the side portions as in the case of the pressed portions 6 and 7. It will be evident that the pressed portions 8 and 9 could, if desired, extend for the full 75 width of the side members 2 and 3. The extreme outer portion of side member 2 is folded over for forming a flap 10, while the extreme end of side member 3 is provided with a turned-over portion defining a flap 80 11, which flap is preferably secured to the body of side member 3 along line 12 by any desired means, as a suitable adhesive. Arranged to slidably fit within the loop formed by the turned-over portion 11 are 85 sliding clips 13 and 14. These clips as more clearly shown in Figs. 3 and 4 are formed with a body 15 having a slot 16, and with a turned-over portion 17 arranged with a curved end 18. The turned-over 90 portion 17 is designed to be resilient so as to normally press against the side 2 when the envelop is folded to the position shown in Fig. 2. In order that the members 13 and 14 may be properly held in place eyelets 95 19 are provided which will not only hold in place the members 13 and 14 but guide the same in their reciprocatory movement. In order that these members may be properly removed or disconnected from 100 side 2 a pressed-out or raised portion 20 is formed in each of the members 13 and 14. By this structure the clips may be engaged by the thumb and forced outwardly as shown in Fig. 1, whereby the side 2 may be 105 unfolded.

By constructing the envelop as described with the various pressed portions 6, 7, 8 and 9, various sized articles may be placed in the envelop and the same properly folded and 110 locked in a folded position by the clips 13 and 14. The envelop in fact not only acts

as an envelop, but as a document holder or file, and automatically adjusts itself to the contents whether the same has been increased or decreased. It will also be noted that the clips 13 and 14 are provided with notched-out portions 21 at the edges, whereby the clips may be easily moved when it is not desired to use the pressed-out or raised portions 20.

10 What I claim is—

In an envelop of the class described, a substantially rectangular body, foldable side and end members connected with said body, said foldable side and end members being 15 rectangular whereby when the same are folded there will be no openings at the corners, each of said side and end members being provided with crimped or corrugated portions so as to allow a bending action of 20 said members substantially at any point, one of said side members being provided

bers being provided with a folded-over end having the edge secured in place, a pair of 25 eyelets on each side extending through said last mentioned folded-over portion, and a sliding locking clip for each pair of eyelets, said clips having bodies extending into said folded-over portion, said bodies being 30 formed with slots for accommodating said eyelets, each of said bodies being provided with a folded-over end for clamping the opposite side against movement, and with a 35 notch on each side for receiving the operator's fingers when applying power to the flaps for moving the same to an outer position.

In testimony whereof I have signed my name to this specification in the presence of 40 two subscribing witnesses.

PETER ALBERT HOFFMAN.
